UNITED STATES PATENT OFFICE.

CLINTON J. HIXSON, OF EAST ORANGE, NEW JERSEY.

CIRCUIT-INTERRUPTER.

1,015,442.

Specification of Letters Patent.

Patented Jan. 23, 1912.

Application filed February 23, 1907. Serial No. 359,008.

To all whom it may concern:

Be it known that I, CLINTON J. HIXSON, a citizen of the United States, residing in East Orange, county of Essex, and State of New Jersey, have made a new and useful Invention in Circuit-Interrupters, of which the following is a specification.

My invention is directed particularly to circuit interrupters for use generally in the electric art and designed to bring about the absolute rupture of electric arcs without damaging effects to the electrodes or circuit interrupting parts, and it has for its objects—First, to provide what I term a “magnetic electrode” so constructed and arranged as to draw the arc, when established, under, over or through such electrode, for the purpose of effectually disrupting it. Second, to provide such a magnetic electrode with an improved form of yieldingly supported adjustable electrode intermediate the magnetic electrode and the rotary or movable electrode. Third, to provide a more effective circuit interrupter having a fixed, a rotary, and an intermediate yieldingly supported electrode.

My improvement will be fully understood by referring to the accompanying drawings, in which—

Figure 1 is a part sectional, part side elevational view of the entire device as applied to a switch or circuit interrupter, the yieldingly supported intermediate electrode and the movable or rotary part of the switch being shown in elevational view. Fig. 2 is a vertical sectional view taken through Fig. 1 of the broken line $x-x$ and as seen looking therat from right to left in the direction of the arrows. Fig. 3 is a sectional view of a modified form of that part of the invention which I term the “cooling chamber or channel.” Fig. 4 is a similar view of a modified form of the same part; and, Fig. 5 is a similar view of a still further modified form in which the cooling chamber or channel constitutes a part of the supporting base of the magnetic electrode.

Referring now to the drawings in detail 1 represents an insulating base for the magnetic electrode and the intermediate yieldingly supported electrode, and 2 represents two vertical standards which support the magnetic electrode proper, the same being composed of two heads 3, 3, and an intermediate core of magnetic material around which latter is wound the insulated mag-

netic coil 4 connected at one end to the binding post 5 and the other to one of the magnetic heads 3, or in such way as to be in good electrical contact with the entire magnetic shell.

6 and 7 represent respectively non-magnetic members preferably of good conducting material, the former of which immediately surrounds the magnetizing coil 4, the latter being secured between the outer edges of the heads 3, 3, in the manner shown in Fig. 1, said parts constituting as combined with the aforesaid heads what I term the cooling chamber or channel for the arc. 8 represents that part of the magnetic electrode designed to convey the working current from the entire magnetic electrode to the yieldingly supported intermediate electrode, and preferably constitutes a renewable tip, surface, or part secured between the heads 3, 3, by screws, as shown. 9 represents a rotary or movable part of the electrode of the switch pivotally supported at 10 and provided with a rotating handle 11, this structural form being shown for the purpose of best illustrating the general nature of my improved device which is adapted for use generally in the arts.

12 is a yielding support for the intermediate movable electrode or part and is secured at its lower end to the base 1; 13 constituting that part of the intermediate electrode adapted to bear upon the part 9 as the switch is rotated. 14 constitutes the supporting part of the renewable tip or surface 16 for the intermediate electrode, said part being pivoted at 15 and having vibratory movement at its upper end to and from the part 13; 17 being an adjustable bolt, 18 a spiral compression spring, and 19 an adjustable nut adapted to be located behind a lug or extension on the part 13, the entire arrangement being such that variable adjustment may be effected between the renewable tip or surface 16 of the intermediate electrode and the tip or surface 8 of the magnetic electrode.

The operation is substantially as follows:—The circuit being open between the renewable tips or surfaces 8 and 16 the attendant rotates the rotary or movable part 9 through the agency of the handle 11 from left to right, thereby causing the yieldingly supported intermediate electrode and its tip 16 to come into electrical contact with the tip 8, thus establishing the circuit. A fur-

ther movement of the handle 11 places the adjustable spiral spring 18 under compression, thereby assuring good yielding electrical contact between the parts. When the 5 current flow is thus established the magnetic electrode is fully energized so that on disrupting the circuit an arc is drawn through the cooling chamber or channel, whereby it is cooled and extinguished.

10 In Fig. 3 I have illustrated a cooling chamber or channel in which the magnetic heads 3, 3, and the outer member 7, 7, of the cooling chamber are provided with radiating ribs 20 of increased surface for giving 15 a greater radiating effect than is possible with the surfaces disclosed in Figs. 1 and 2. Similar ribs are shown on the interior of the heads 3, 3, which serve to bring a greater cooling surface and mass of 20 metal in contact with the arc to be extinguished, at the same time increasing the magnetic flux passing through the chamber.

In Fig. 4 I have illustrated a modified disposition or shape of the cooling chamber 25 or channel from that illustrated in Fig. 2. In the form shown in Fig. 4 the magnetic intensity is increased by bringing the magnetic heads or pole-pieces closer together.

In Fig. 5 I have illustrated a still further 30 modified form in which the length or cooling surface is materially increased by so arranging the parts that the support of the entire magnetic electrode is hollow. In other words, in this instance the cooling 35 chamber or channel is continued from about or around the coil downward to the base 1. In this form 21 represents a barrier for preventing the arc from flowing around the inner or surrounding surface 6 which incloses 40 the coil, said barrier being intended to force the arc to pass through the longer channel over and downward, as will be apparent on inspection of the drawings.

Although I prefer to construct this cooling 45 chamber or channel with outer and inner surfaces 6 and 7 between the magnetic heads 3, 3, and with openings to the exterior air, as shown, these features may be departed from and still come within the scope 50 of my most generic claims. To illustrate, the members 7 may be entirely done away with, thus leaving the cooling chamber or channel open exteriorly to the air; or, it may be modified in various ways so long as 55 a conveying channel of any nature be provided for thus cooling the arc as it is drawn into the magnetic field, by virtue of the action of the coil 4 upon the core and heads 3, 3, the essence of my invention in this particular lying in the establishment of a conducting cooling arc channel.

Having thus described my invention what I claim and desire to secure by Letters Patent of the United States is—

65 1. In an electric circuit interrupting de-

vice for relatively high potential circuits two circuit interrupting parts, one of which parts is rigidly sustained upon a fixed standard and the other part is movable and sustained upon a yielding support which normally tends to separate it from the stationary contact; in combination with a rotary part of cam-like or eccentric nature provided with means for rotating it; together with a rigid contacting member operatively connected with the yielding support and adapted to have continuous contact with the surface of the eccentric part, substantially as described. 70

2. In an electric circuit interrupting device for relatively high potential circuits two circuit interrupting parts, one of which parts is rigidly sustained upon a fixed standard and the other part is movable and sustained upon a yielding support which normally tends to separate it from the stationary contact; in combination with a rotary part of cam-like or eccentric nature provided with means for rotating it; together with a rigid contacting member operatively connected with the yielding support and adapted to have continuous contact with the surface of the eccentric part, the movable part being provided with adjusting means for varying its contact relation with the fixed part, substantially as described. 75

3. Means for breaking an electrical circuit of relatively high potential and great current value, embracing three circuit interrupting parts one of which is stationary and the other two movable, the intermediate part being movable and provided with means for yieldingly holding it always in contact with the other movable part and also provided with adjustable means for varying its distance from the stationary part, said stationary part being of magnetic material and included in the magnetic field of a coil located in direct circuit with the circuit to be interrupted substantially as described. 100

4. Means for breaking an electrical circuit of relatively high potential and great current value, embracing three circuit interrupting parts, one of which is stationary and the other two movable; one of the movable parts being provided with means for yieldingly holding it always in contact with the other and also provided with adjustable means for varying its distance from the stationary part; said stationary part being of magnetic material and included in the magnetic field of a coil adapted to magnetize it, said coil being connected in direct circuit with the circuit to be interrupted; together with a cooling chamber which surrounds the aforesaid coil and is open on both sides, substantially as described. 115

5. Means for breaking an electrical circuit of relatively high potential and great current value, embracing three circuit inter- 120

- rupting parts one of which is stationary and the other two movable; the intermediate part being movable and provided with means for yieldingly holding it always in contact 5 with the other movable part, and additional means for varying its distance from the stationary part, which stationary part is of magnetic material and is located in the magnetic field of a coil included in the circuit to be interrupted and adapted to magnetize it; together with a cooling chamber which surrounds the aforesaid coil, the walls of said chamber being provided with radiating ribs, substantially as described.
- 10 6. A circuit interrupting device for interrupting electrical currents of relatively high potential and great current value, embracing a stationary contacting part of magnetic ma-

terial and a movable contacting part which is yieldingly supported and operatively connected with means for varying its relative position to the stationary part; in combination with a magnetic coil located in a circuit to be interrupted and adapted to magnetize the stationary part; together with non-magnetic inclosing members operatively connected to the heads of the coil and adapted to constitute an air chamber surrounding the stationary part, substantially as described.

15 In testimony whereof I have signed my name to this specification in the presence of two subscribing witnesses.
